SIGNALING SYSTEM

Edward J. McCarthy, Newton, Mass., assignor to
 The Gamewell Company, Newton Upper Falls,
 Mass., a corporation of Massachusetts

Application July 2, 1932, Serial No. 620,666

7 Claims. (Cl. 177—367)

Certain signaling systems, as for example, fire alarm and similar installations, operate by interrupting normally closed and energized signaling circuits with apparatus in series connection. Such systems have to be arranged for service under faulty conditions of various kinds, like grounded, interrupted or shunted lines, and in some instances they are for that purpose equipped for signaling through an emergency conductor, usually the ground, which can be associated, if the necessity arises, with any of the signal transmitting stations, either by hand or automatically. In systems of this type, the signal transmitters, referred to as alarm boxes, connect the signal circuit to ground, sometimes only during signaling under certain circumstances, sometimes during each signaling period, or, with another type of alarm boxes, once for each code signal impulse, no matter whether the circuit is sound or not. Such systems may also employ different kinds of current for normal and emergency operation, respectively, as for example, the systems described and claimed in the copending applications of Clarence E. Beach, Serial No. 573,151, filed November 5, 1931, for "Signaling systems", Patent No. 2,018,656, dated Oct. 29, 1935, and Frank R. Bridges, Serial No. 620,683, filed July 2, 1932, for "Signaling system", both assigned to The Gamewell Corporation.

With systems of this type, which are adapted to take care of almost any possible emergency condition, it is nevertheless possible that in spite of the use of alarm boxes incorporating the well known non-interference and succession features, a transmitting or receiving station may be virtually eliminated from the signaling circuit. For example, if two points of a fire alarm circuit are simultaneously grounded, these ground connections may establish a shunt around intermediate boxes or stations as fire houses with acoustic signal receivers, thereby rendering the shunted apparatus inoperative, as will be explained in detail hereinafter. It is, therefore, one of the principal objects of the present invention to provide a signaling system, and signal transmitting equipment therefor, which eliminate the danger of shunting out signaling apparatus intermediate two grounded points.

In another aspect, the present invention permits the use of comparatively simple signal initiating apparatus which nevertheless, in circuits of the kind referred to, provide a high degree of certainty and security of the operation of their non-interference and succession equipment. This advantage is obtained by organizing the signaling

circuit in such a manner that the grounding of a signal transmitter during normal operation can not influence the operation of these aforementioned devices. Accordingly, other objects of the present invention are to provide a signaling circuit of the type referred to, whose operation is not detrimentally influenced by the grounding of a signal transmitter during normal operation, whereas it permits emergency operation over ground as emergency conductor, to provide alarm boxes which prevent any flow of a certain kind of current, for example direct current, to an emergency conductor, whereas they permit the corresponding flow of another kind of current, for example alternating current, and to provide a signaling circuit which permits the improvement of existing alarm systems merely by adding simple and inexpensive elements to the old installation.

These and other objects and advantages are obtained by connecting, in the ground path of signal initiating devices or alarm boxes used in circuits employing different types of current for normal and emergency signaling, devices which prevent the flow through the emergency conductor of the current which is only intended for normal operation, as will be explained in detail in the following description of two embodiments of the invention by way of example, with reference to the appended drawing, in which:

Fig. 1 is a connection diagram of a fire alarm installation with separate alternating current and direct current supplies, incorporating the present invention; and

Fig. 2 is a similar diagram showing the invention applied to a different current supply system, and under different emergency conditions.

Fig. 1 shows a circuit employing direct current and alternating current for normal and emergency operation, respectively, according to the above-identified copending application of Frank R. Bridges, Serial No. 620,683. This circuit comprises a circuit loop L with station terminals 1 and 2, signal transmitting and signal manifesting devices represented in Fig. 1 by alarm boxes M, N and O and bell F, the latter symbolizing the acoustic signal manifesting device of a fire house which may be included in signal loop L. As described in detail in the above-identified copending application, loop L is supplied with alternating current from a transformer T whose secondary 4 is connected to ground and over-leads 5 and 6 to terminals 1 and 2, whereas the primary 3 is supplied from a suitable alternating current source. Condens-

ers 7 and 8, and choke coil 9, respectively, prevent interference of the two current supplies. Signal manifesting devices 11, 12 and 13, as for example, directly recording instruments, or 5 layouts of repeater circuits, are connected as indicated in Fig. 1, and herein referred to as recorders.

The alarm box M, shown in detail in Fig. 1, is representative of the type of signal transmitters which ground the signal circuit during each 10 signaling period, but it is understood that my invention may be applied to other types of alarm boxes.

Box M is somewhat similar to the signal transmitter disclosed in Patent No. 1,244,587 for "Successive non-interference box" to F. W. Cole, dated October 30, 1917, but has additional means for sending signals through ground as the emergency conductor. It comprises shunting contacts 81, 20 normally closed signaling contacts 84, 86, and normally open contacts 82 and 83, both pairs of contacts being operated by the code wheel 88. As indicated in the drawing, an insulating block 87 is arranged intermediate levers 82 and 25 84, so that lever 82 can move independently of 84, if the latter is retained in raised position by pin 80 associated with the armature of non-interference magnet 85 (operative only with direct 30 current) in such a manner that 80 moves underneath 84 if the armature is deenergized. Normally code signals are sent by contacts 84 and 35 86 opening and closing in accordance with the code represented by the teeth of wheel 88 whereas, if the line is interrupted due either to a line 40 break, or the fact that another box is already signaling, magnet 85 is deenergized and its armature drops, moving pin 80 underneath lever 84, thereby preventing it from leaving contact 86. Lever 82 continues to cooperate with the code 45 wheel, so that signals can be despatched over ground and a portion of the normal signaling circuit. According to the present invention condensers 91 and 92 are connected between the two terminals of the box and grounding contacts 50 82 and 83. It will be understood that instead of condensers 91 and 92 a single condenser could be interposed between contacts 82, 83 and ground, as for example, indicated by condenser 90 shown in the other boxes. The disposal of the condenser or condensers will mainly be governed by the design of the alarm box with which they are used. In the present case the condenser arrangement offers altering current paths to 55 ground from both sides of the line, these paths including only the grounding switch and not the non-interference coil. If only a single grounding condenser is used, it must be connected between one of the two terminals of the alarm box in series with switch 82-83, in order to avoid a 60 continuous short circuit which would exist if the single condenser were connected between ground and contact 83 of Fig. 1, by omitting condensers 91 and 92. It will be evident that under certain conditions, as for example when signaling 65 through ground with a broken loop, an alarm box with only one condenser necessarily often introduces magnet and normal contacts into the signaling circuit. If unfavorable conditions exist, as when a long portion of the loop is included in 70 the circuit, or if the ground is poor, or if the magnet is interrupted, signaling will become uncertain or even impossible with a single condenser box. With the two condenser arrangement shown for alarm box M of Fig. 1, the emergency 75 circuit includes only contacts 82-83 and the re-

spective condenser, no matter how the emergency circuit is constituted, so that emergency signaling is rendered more certain.

In the modification according to Fig. 2, L is again an outer signal circuit or loop, including alarm boxes M, N and O and manifesting station F, and leading to station terminals 1 and 2. A rectifier bridge R has four terminals 51, 52, 53 and 54 and four asymmetric conductors 61, 62, 63, and 64 which permit the passage of current substantially only in the direction of the arrows or their symbols. Terminals 51 and 52 are connected to the secondary 59 of a transformer S whose primary 58 is supplied with alternating current from any suitable source. Terminal 52 is grounded through signal manifesting device 46, and manifesting devices 47 and 48 are connected in the leads from terminals 53 and 54 to terminals 1 and 2. In a system of this type, the loop L is normally supplied with direct current 20 derived from terminals 53 and 54, whereas under certain emergency conditions, when the loop L is grounded either through the mechanism of an alarm box or due to a faulty line, alternating current impulses flow between terminals 52 and/or 25 53 and 54, respectively, as described and claimed in the above-identified copending application Serial No. 573,151.

Referring to Fig. 1 the operation of my signaling system under normal conditions is as follows: If a single box, for example M, is pulled, switch 81 opens and signaling takes place with direct current, contacts 84 and 86 interrupting the normally closed circuit, thereby initiating signal manifestations at centrally located receivers, as for example, recorder or relay 13, and also at alarm devices included in the signal loop, as for example, bell F. The grounding of the circuit through contacts 83 and 82, condensers 91, 92, is inconsequential as far as reception at 13 is concerned, since the direct current is arrested at 91 and 92, and the direct current circuit therefore is not disturbed by the closing of contacts 82 and 83. Recorders 11 and 12 will receive the same signals, given at contacts 82 and 45 83, and transmitted through condensers 91, 92, ground and secondary 4.

If several boxes are pulled at almost the same time, the first box takes possession of the line, whereas the non-interference mechanisms of all boxes which may be pulled later prevent these from interrupting the normal signaling circuit by retaining lever 84 in raised position. Again, the grounding at 82 and 83 is inconsequential 55 due to the fact that direct current can not flow to ground over the condensers. Recorders 11 and 12 will receive alternating current signals as above described.

Assuming that boxes without condensers are used, one of the advantages of my invention will be apparent from the following consideration. If, for example, box N is pulled first, and boxes M and O subsequently, the non-interference devices of N and O arrest contacts 84 and 86 of 60 their respective boxes, but the grounding contacts 82 and 83 of M and O shunt box N for direct current and interrupt its signaling, the signals at the central station as well as at F becoming unintelligibly garbled. With condenser 65 equipped boxes according to the present invention, direct current circuits including the ground can not be established, whereas the alternating current can not interfere with proper signaling 70 (although it is short circuited over the con- 75

densers) since the non-interference magnets are only responsive to direct current.

In case of an accidentally grounded circuit, as indicated at *x* of Fig. 1, conditions are similar, and non-interference equipment as well as line manifesting devices operate properly with direct current which can not flow over ground, there being only one ground connection available for the direct current, namely *x*.

10 Assuming that boxes without condensers are used, a condition similar to that above discussed would arise. With an accidental ground at *x*, box *N* operating, and box *M* subsequently pulled, *M* and ground *x* would shunt *N*, box *M* interrupting the signaling of *N*, which is especially undesirable if it occurs during any portion of the code signal transmitted by *N*.

If the circuit should be accidentally broken, as indicated at *y* of Fig. 1, the direct current 20 is interrupted and the system would be inoperative without the presence of an alternating current circuit. In this case, assuming that for example box *M* is pulled, alternating current is transmitted by contacts *82* and *83* through the 25 condensers and ground, and received by recorder *11*. The non-interference apparatus does not respond to alternating current and does not, therefore, operate under these emergency conditions. Bells intermediate the power supply and the operating box function normally, provided they respond to alternating current.

In case of a short circuit *z*, as indicated in Fig. 2, the shunted apparatus *N* and *F* carry no direct current, which is diverted through *z*, 35 so that no direct current signals originating with *N* can be received. However, contacts *82* and *83* transmit alternating current signals through ground, as above described, the signals being received at *46* and at *F*. Under such conditions 40 the non-interference features of the shunted boxes are inoperative, whereas the boxes outside of the short circuit function normally with direct current, and therefore also with non-interference.

45 A further advantage of my new systems consists in the favorable influence of the box condensers with respect to stray currents. It is a well known fact that the circuits of grounded fire alarm systems are often disturbed by stray currents originating, for example, in trolley lines. Such unidirectional stray currents are successfully excluded from the normal operating circuits by condensers arranged according to the present 50 invention as will be apparent from the preceding description without further explanation.

Also, the new arrangement affords a protection against the harmful effects of accidental contacts with high power alternating current lines. Assuming that the boxes are not provided 55 with condensers, and that an alternating current line *H* accidentally touches the signaling loop as indicated at *w* of Fig. 2, the alternating current of *H* would pass to ground through the station and damage the apparatus of the latter. The box condensers according to my invention, however, offer alternating current paths to ground so that the alternating current of *H* is diverted from the station due to the fact that the station impedance is high compared to the 60 box impedances. The normally open grounding contacts *82* and *83* are thereby easily bridged by the power current, especially if the gap between these contacts is accordingly dimensioned.

It will be apparent from the foregoing 65 description that the underlying principle of my

invention, namely, the separation of normal and emergency operation of signal initiating devices by making their ground connection operative only for the emergency current, may be carried out in ways different from those herein disclosed. For example, different alarm box mechanisms may be used, or asymmetric conductors, as for example rectifiers, may be employed instead of condensers for excluding direct current from ground, or two alternating 10 currents of different frequencies may be used, whereby one frequency can be excluded from ground by suitable filtering equipment.

It should be understood that the present disclosure is for the purpose of illustration only 15 and that this invention includes all modifications and equivalents which fall within the scope of the appended claims.

I claim:

1. A fire alarm box for signaling systems operating with direct and alternating currents comprising two line terminals, a normally closed line signaling switch and a non-interference magnet operating only on direct current in series across said terminals, means controlled by said magnet 25 upon deenergization thereof for arresting said line signaling switch in closed position, two condensers serially connected across said terminals, a ground signaling switch intermediate ground and a point of the conductor connecting said condensers, and signal initiating means for opening and closing respectively said switches in synchronization, said condensers forming with said ground signaling switch paths exclusive of said line switch and said magnet. 35

2. A fire alarm box for signaling systems operating with direct and alternating currents comprising two line terminals, a normally closed line signaling switch and an exclusively direct current operative non-interference magnet connected in 40 series across said terminals, a normally open emergency signaling switch and in series thereto a capacitance connected intermediate one of said terminals and ground, means for concomitantly but independently actuating said line switch and 45 said emergency switch, and means controlled by said non-interference magnet for arresting said line switch in closed position upon deenergization of the magnet.

3. A signaling system comprising a normally 50 closed signal circuit supplied with unidirectional current, an alternating electromotive force between said circuit and ground, individually grounded signaling means serially connected in said circuit for sending signal impulses through 55 said circuit and through said circuit and ground and having means responsive to direct current only for suppressing upon deenergization thereof, the sending of said impulses through said circuit, but permitting the sending of said impulses through said circuit and ground and means in said individual ground connections of each signaling means for excluding flow of direct current from said circuit to ground. 60

4. A signaling system comprising a normally 65 closed signal circuit supplied with unidirectional current, an alternating electromotive force between said circuit and ground, individually grounded signal transmitters serially connected in said circuit for opening and concomitantly grounding said circuit according to a signal code and having means responsive to direct current only for arresting, when deenergized, the opening 70 of said circuit but permitting signaling through 75

ground, and a capacitance intermediate each transmitter and its ground connection.

5. A signaling system comprising a normally closed signal circuit supplied with unidirectional current, an alternating electromotive force between said circuit and ground, signal transmitters serially connected in said circuit including a ground connection, means for despatching signal impulses by opening said circuit and by connecting said circuit and said ground, and non-interference equipment operative only with direct current rendering said transmitters ineffective for opening said circuit but permitting signal despatch through ground, and means in each transmitter for arresting the flow of direct current from said circuit through said transmitters to ground.

6. A fire alarm box for signaling systems operating with direct and alternating current comprising two line terminals, a normally closed line signaling switch and an exclusively direct current responsive non-interference magnet connected across said terminals, a normally open ground signaling switch connected on one side through a capacitance to each of said terminals and on the other side to ground, means for concomitantly but independently actuating said

switches, and means controlled by said magnet for retaining said line signaling switch in closed position upon deenergization of the magnet.

7. A signaling system comprising a normally closed metallic signal loop serially including two station terminals, direct current responsive signal receptive means, a direct current source, and signal transmitting stations; each station having two line terminals and therebetween in series normally closed loop contacts, and non-interference equipment responsive only to direct current and retaining said loop contacts closed upon deenergization thereof, normally open ground contacts between said line terminals and ground, and means for actuating said contacts to form signal impulses; an emergency circuit serially including the ground, an emergency signal receiver, an alternating current source, one of said station terminals, part of said loop, one of the line terminals and the ground contacts of a signal transmitting station; and in each signal transmitting station condensers intermediate said ground contacts and each of said line terminals for preventing the flow of direct current in said emergency circuit and excluding said non-interference equipment from any possible emergency circuit.

EDWARD J. McCARTHY.
